United States Patent

Des. 239,485
Patented Apr. 13, 1976

239,485

COMBINED CHAIR AND LUGGAGE RACK THEREFOR

Morton I. Thomas, Monroe, N.Y., assignor to
Temco Products, Inc., Passaic, N.J.

Filed June 4, 1973, Ser. No. 366,971

Term of patent 14 years

Int. Cl. D6—01

U.S. Cl. D6—67

The figure is a front perspective view of a combined chair and luggage rack therefor. The side of the chair not shown is a mirror image of the side shown while the back is plain and unornamented.

I claim:

The ornamental design for a combined chair and luggage rack therefor, substantially as shown and described.
